COMBINATION GARDEN SPADE, HOE AND WEEDING TOOL

Arthur M. Mitchell, 2200 Michigan Blvd.,
West Sacramento, Calif.

Filed May 12, 1964, Ser. No. 79,939

Term of patent 14 years

(Cl. D35—2)

FIG. 1 is a side elevation of a combination garden spade, hoe and weeding tool showing my new design;

FIG. 2 is a top plan view thereof with the handle member fragmentarily shown for convenience of illustration;

FIG. 3 is a bottom plan view thereof;

FIG. 4 is an elevation as seen from the rear of FIG. 1; and

FIG. 5 is a side elevation taken 180° from FIG. 1.
I claim:

The ornamental design for a combination garden spade, hoe and weeding tool, substantially as shown and described.
